MOLD FORM APPARATUS

William Allen Jennings, Des Moines, Iowa, assignor to Economy Forms Company, Des Moines, Iowa, a corporation of Iowa

Application May 27, 1933, Serial No. 673,214

4 Claims. (Cl. 25—131)

My invention relates to that class of forms for concrete structures in which there is employed a number of panels detachably connected with each other and detachably connected to structural wooden beams for supporting the forms in their proper positions.

The objects of my invention are to provide metal panels of this class of simple, durable and inexpensive construction and of light weight, and so constructed and arranged that they are readily and easily assembled and perfectly alined so that the resultant concrete wall formed by them will be smooth and free from offsets and irregularities such as has been the result of the use of other mold panels now in common use.

A further object is to provide improved, simplified and economical means for detachably connecting together the panels of two opposed form walls by means of spacing bars extending through the panels and the concrete wall.

More specifically in this connection it is my object to provide spacing bars having straight smooth parallel surfaces and so arranged that during the removal of the panels from the concrete wall these spacing bars may be readily and easily withdrawn through the concrete wall without chipping or marring the adjacent surfaces, so that the small openings left in the wall by the spacing bars may be readily and easily covered over smoothly with concrete; and further in this connection it is my object to provide improved and simplified means for accurately and quickly securing the panels to the ends of the spacing bars in properly spaced positions and for quickly and easily removing the panels from the spacing bars.

A further object is to provide an improved panel in which the entire panel is made of relatively thin sheet metal and its marginal edges are formed of the same metal bent at right angles and reinforced in such manner as to insure perfect alinement of the inner faces of the panels when assembled in a mold form; and in this connection it is my object to provide a mold panel of this class in which the panel and its reinforcing bars and marginal edges may all be readily and quickly manufactured with the use of dies and formers, and whereby the panels and panel alining and locking devices may be used interchangeably and produce smooth concrete walls in all instances.

My invention consists in the construction, arrangement and combination of the various parts of the device, whereby the objects contemplated are attained, as hereinafter more fully set forth,

pointed out in my claims, and illustrated in the accompanying drawings, in which:

Figure 1 shows an outer face view of a number of panels embodying my invention supported in position by structural beams and illustrating the means for alining and holding into alinement adjacent side by side panels and for locking the flanges of the adjacent side panels together.

Figure 2 shows an enlarged detail sectional view on the line A—A of Figure 1.

Figure 3 shows an outer face view of one of my improved panels.

Figure 4 shows an enlarged detail view of the outer face of one corner of a panel and illustrating my improved alining device with a locking pin in position for holding the alining pin.

Figure 5 shows a sectional view on the line 5—5 of Figure 4.

Figure 6 shows a sectional view of a portion of my improved panel illustrating the closure device for the slots for receiving the spacing bars.

Figure 7 shows a sectional view on the line 14—14 of Figure 6; and

Figure 8 shows a detail perspective view of the closure device.

Referring to the accompanying drawings it will be seen that my improved panel is formed of a flat sheet metal body portion 20 with all four marginal edges 21 thereof bent outwardly at right angles and welded together at their corners.

This operation of bending these marginal edges 21 is in practice accomplished with suitable forming dies so that each panel, and particularly the marginal edges thereof, are exact duplicates of each other, and by this means I obtain a relatively strong and rigid structure, and at the same time provide marginal edges exactly alike in each of the series of panels with the result that when assembled to form a mold wall there will be no rough or uneven surfaces at the outer surfaces of the flanges, and the outer faces of all panels will be flush, whereas with those now in common use where structural bars are secured to the outer edges of the panel body to form marginal edges, the edges and faces of the panels are frequently out of line, resulting in rough and uneven concrete walls.

Another advantage obtained by the use of the out-turned sheet metal flanges is that before turning them the necessary alining and locking openings or perforations may be formed therein by gang punches, and each flange is provided with the same openings from the same dies so

that when assembled in side by side positions these openings will accurately aline.

These openings as illustrated in Figure 2 comprise a series of openings 22 for the alining pins 5 and a series of openings 23 for the devices for clamping the forms to the structural beams, or for alining pins and also the locks for holding together the marginal flanges of two adjacent panels.

10 In addition to the marginal edges 21 I provide in the upright central portion of each panel two spaced apart flanges 24, each being made of sheet metal in the same manner as the rib 25 shown in Figure 5, and in addition thereto I provide a series of reinforcing ribs 26 extending from the flanges 21 to the ribs 25. All of these flanges and ribs just described are formed as clearly shown in Figure 5 by bending the outer edges thereof inwardly at 27 and extending the openings 23 15 through both layers of sheet metal ribs. This forms a rigid construction, is easily made, and makes the metal surrounding the openings 23 thick enough to withstand long continued use without change or deterioration.

25 I have found that panels as constructed can be readily made by machinery so that they are perfect duplicates of each other and at the same time the weight and expense is greatly reduced, making them easier to handle and install.

30 For the purpose of alining two side by side panels and permanently holding them in alined positions, I have provided on each side of each panel a brace 28 secured to the panel and to the adjacent flange and rib, and having therein two 35 openings, one to receive the pin as shown at the top in Figure 5, and the other indicated by the numeral 29 to receive a locking pin.

Adjacent to and spaced apart from the rib 28 is a lug 30 having an opening therein to receive 40 a locking pin as shown in Figure 4. In the space between each of the ribs 28 and the adjacent flange 21 I provide a slot 31 to receive a spacing bar hereinafter described, which spacing bar, as shown in Figure 5, has an opening 32 at each end.

45 In assembling two adjacent side by side panels, I place them in adjacent positions with their flanges 21 together, and then accurately aline them by inserting an alining pin 33 having a tapered point 34 and a right angle handle 35.

50 This pin is passed through the opening in the rib 28 through the opening in the spacing bar and then through the opening 22 in the flange 21, and then through the corresponding opening in the adjacent flange 21. In this manner the 55 two flanges of the adjoining panels are accurately brought into and held in alinement.

The handles 35 project outwardly from the panels, so they may be easily manipulated with the operator's hand, and by turning them it is 60 very easy to cause the tapered end 34 to enter and bring to alinement the two panels, and then when the pin is further pushed through the panels and around the body portion, the pins accurately fit the openings in the panels and hold them in 65 alinement. Then the handle 35 may be pushed down against the outer face of the panel where it will be held against longitudinal movement by the lug 30.

In some instances it is desirable to lock this 70 handle in said position, and for this purpose I have provided an opening in the lug 30 and the opening 29 in the rib 28 to receive a similar pin to the one 33, and this pin when placed in said openings, as shown in Figure 4, locks the handle 75 35 in position, and at the same time locks the

spacing bar in accurately spaced position to the panel.

The spacing bar indicated by the numeral 36 is made of a piece of straight flat metal and has the openings 32 at its ends. This bar is inserted 5 through the openings 31 in two opposed panels, and when the alining and locking pins 33 are placed in position, the two panels are accurately spaced apart.

One of the substantial advantages of my invention is in connection with these spacing bars, and when the concrete wall has partly set and hardened, and it is desired to remove the panels, the locking pins are removed and then the operator may, by inserting a proper tool in the opening 32 10 in one end of the spacing bar, withdraw the spacing bar through the concrete wall, and since this spacing bar is straight and smooth it may be withdrawn without marring the wall, and the small openings left in the wall may be readily 15 and easily filled with concrete or other material, leaving smooth walls without metal in it which will rust and corrode and otherwise mar the wall surface.

It will be noted upon reference to Figure 3 that 25 I have provided a number of these slots 31, and in many instances a less number of spacing bars 36 are employed. It is, therefore, desirable that means be provided for closing these openings 31, which are not in use, and for this purpose I have 30 provided a block 37 secured to the outer face of the panel adjacent to each of said slots. This block has recesses 38 formed at each end between the panel and the adjacent portion of the block, and the block is formed with a slot 39 extending 35 completely through it in line with the slot 31.

The closure plate as illustrated in Figure 8 is made of spring metal and comprises a flat body portion 40 of the size and shape of the slot 31, and outwardly turned end portions provided with lugs 41. These closure plates are inserted through the openings 39 in the blocks 37 and the lugs 41 are bent inwardly during this operation, and then spring outwardly into the recess 38 where they are yieldingly held in position for forming 45 a smooth flat closure for the slots 31. They may be removed from the blocks and slots by simply pressing inwardly upon the outer faces of the closure plates.

In practical use with my improved mold form, 50 I find that by making the panels with their marginal edges bent at right angles to form reinforcing flanges, and by bending the edges of the flanges inwardly against the bodies of the flanges, and then by forming the openings in these flanges with gang punches, I provide a panel structure of inexpensive construction and of light weight, and which when assembled with other panels in a mold form will produce finished concrete walls 55 so smooth and uniform that they need not be remodeled or repaired after the concrete forms have been removed, and are ready to receive paint or other finishing material.

I have also found that with my improved panel 60 alining device an operator may very readily and quickly insert the alining pins, bring the panels to alined position, and firmly hold them in such position.

After the operator has determined what number 70 of spacing bars are to be employed on each panel, and has placed them in position, he can readily and quickly close the spacing bar openings by inserting from the outer faces of the panels the closure plates for these openings, and these 75

closure plates will be held in position firmly enough for practical purposes.

I claim as my invention:

1. In a form device of the class described, the combination of a form panel formed with a spacing bar slot, and means for sealing said slot, comprising a block secured to the outer face of the panel and formed with notches on opposite sides of its interior adjacent said slot, and a flexible sealing plate shaped to fill said slot and having shoulders at opposite sides shaped to enter said notches.
2. In a form device of the class described, the combination of a form panel formed with a spacing bar slot, and means for sealing said slot, comprising a block secured to the outer face of the panel and formed with notches on opposite sides of its interior adjacent said slot, and a flexible sealing plate shaped to fill said slot and having shoulders at opposite sides shaped to enter said notches, said block being formed with a slot in alignment with the slot in the panel shaped to admit said flexible sealing plate from the outer face of the panel.
3. In a mold form apparatus, the combination of a mold form panel having a slot formed therein, two spaced apart flanges fixed to and extended outwardly from the panel on opposite sides of said slot and being formed with aligned openings, a spacing bar extended through said slot and having an opening therein, a pin extended through the openings in the flanges and in the spacing bar, and having a handle extended at right angles relative to the pin, and a third flange on the panel so positioned as to receive said handle between it and the adjacent flange, when the handle is turned to position adjacent the outer face of the panel to thereby prevent withdrawal of the pin.

and having an opening therein, a pin extended through the openings in the flanges and in the spacing bar, and having a handle extended at right angles relative to the pin, and a third flange on the panel so positioned as to receive said handle between it and the adjacent flange, when the handle is turned to position adjacent the outer face of the panel to thereby prevent withdrawal of the pin. 5

4. In a mold form apparatus, the combination of a mold form panel having a slot formed therein, two spaced apart flanges fixed to and extended outwardly from the panel on opposite sides of said slot and being formed with aligned openings, a spacing bar extended through said slot and having an opening therein, a pin extended through the openings in the flanges and in the spacing bar, and having a handle extended at right angles relative to the pin, and a third flange on the panel so positioned as to receive said handle between it and the adjacent flange, when the handle is turned to position adjacent the outer face of the panel to thereby prevent withdrawal of the pin, said third flange and the adjacent flange having aligned openings therein and a second pin passed through said last mentioned opening and over said handle to lock the handle in its position adjacent the panel. 10 15 20 25 30
